CLAIM

The ornamental design for a lamp as shown and described.

DESCRIPTION

1.1 : Perspective view of the lamp in a first position.
1.2 : Right view of the lamp in the position of 1.1.
1.3 : Front view of the lamp in the position of 1.1.
1.4 : Perspective view of the lamp in a second position.
1.5 : Perspective side view of the lamp in a third position.
1.6 : Rear perspective view of the lamp in a fourth position.
1.7 : Perspective view of the lamp in a fifth position.
1.8 : Perspective front view of the lamp in the fourth position.

1.9 : Left view of the lamp in the first position.

1.10 : Rear view of the lamp in the first position.

1.11 : Top view of the lamp in the first position.

1.12 : Bottom view of the lamp in the first position.

1.13 : Rear perspective view of the lamp in the third position.

The broken lines shown in the drawings illustrate portions of the lamp and form no part of the claimed design.
